US00D337524S

United States Patent [19]

Sherman et al.

[11] Patent Number: Des. 337,524[45] Date of Patent:  Jul. 20, 1993[54] BOTTLE

[75] Inventors: Adam Sherman, Brooklyn; Herbert M. Meyers, New Rochelle; Richard C. Edstrom, New York, all of N.Y.; Richard N. Hirst, Teaneck, N.J.

[73] Assignee: Colgate-Palmolive Company, New York, N.Y.

[] Term: 14 Years

[21] Appl. No.: 721,360

[22] Filed: Jun. 25, 1991

[52] U.S. Cl. D9/542

[58] Field of Search ..... D9/542, 541, 539, 538, D9/540, 543, 574, 573; 215/1 R, 1 C

[57]

CLAIM

The ornamental design for a bottle, as shown and described.

DESCRIPTION

FIG. 1 is a front elevational view of a bottle embodying our new design;

FIG. 2 is a side elevational view thereof, rotated 90° from FIG. 1;

FIG. 3 is a rear elevational view thereof, rotated 180° from FIG. 1;

FIG. 4 is a side elevational view rotated 270° from FIG. 1;

FIG. 5 is a top plan view thereof;

FIG. 6 is a bottom plan view thereof; and,

FIG. 7 is a perspective view thereof.

A broken line showing of a cap is for illustrative purposes only and forms no part of the claimed design.
